ATTORNEY

UNITED STATES PATENT OFFICE

VINCENZO PELLEGRINO, OF RYE, NEW YORK

SUSPENDED COVER

Application filed January 20, 1928. Serial No. 248,108.

This invention relates in particular to a suspended cover adapted for the purpose of protecting motor vehicles and the like from dust when stored indoors, or to protect same from the elements when stored out of doors.

The object of the invention is to provide a cover of the class described including a means of raising the cover when not in use as a means of protecting the said cover from damage or misuse.

A further object of the invention is to provide a cover of the class described embodying certain new and novel features herein-after set forth, claimed and illustrated in the following drawing.

Fig. 1 is a side elevational view of my improved cover showing same in a raised position by dot and dash lines.

Fig. 2 is a similar view illustrating another form of my improved cover embodying the same invention.

Fig. 3 illustrates a further form of my improved cover embodying the same invention.

Fig. 4 is a side elevational detail view of the adjustable joiner as embodied in my improved device.

As here embodied my improved device comprises an upright member 10, secured at its lower extremity to the ground, or to the floor of a building. The arm 11 is secured at one extremity, to the upper extended portion of the upright member 10, and is horizontally extended therefrom.

The conventional pulley 12 is rotatably mounted in the usual shieve 13, secured to the arm 11, at or near the extended extremity thereof. A similar pulley 14 is rotatably mounted in a similar shieve 15 secured to the arm 11 in proximity to the upper portion of the upright member 10.

The cover proper 16, preferably canvas, cotton ducks, or the like when used in-doors, or any suitable waterproof material, such as sheet rubber, rubberized sheeting, or the like when used out-of-doors, is of rectangular shaped sheet construction. Ropes 17 are secured to the corners of the sheet 16, and are secured to the ropes 16' intermediate thereof. A plurality of ropes 17' are secured intermediately to the sheet 16, in proximity to

either side of the central portion thereof, and are secured at their extended extremities to the lower extremities of the said ropes, 16'. The ropes 16' are secured to a joiner 21^a hereinafter described in detail, and said joiner 21^a is attached on the rope 21. The rope 21 is extended over the pulleys 12 and 14 and is wound on the drum 23, and secured thereto as at 22. The drum 23 is rotatively mounted in a pin 22^a secured to the lower portion of the upright member 10, and is provided with a crank 23' or handle element. I have also provided a support 22', secured to and extended from the lower portion of the upright member 10 and positioned directly above the said drum 23. It is understood that the rope 21 is looped over the support 22' as at 24', when the cover proper is raised by turning or rotating the drum 23, so as to hold the cover proper in a raised position.

The above described construction is such as will permit my improved cover to be lowered, as designated by the reference numeral 24, as a means of affording protection to motor vehicle 25. Ropes 26 are secured to the corners of the frame 16 and are extended therefrom, and are adapted to be secured to the motor vehicle 25, when my improved device is in a lowered or in use position, as a means of holding my improved cover in position over the said motor vehicle.

In Fig. 2 of the accompanying drawing, I have shown an enclosing member 27 of rigid hollow dome-shaped construction provided with downwardly extended portion 27'. Reinforcing members 29', wire, or the like are adapted to encircle the periphery of the extended portion 27'. Ropes 30 are secured intermediately to the enclosing member 27 and are secured to their upper extended members to the joiner 21^a hereinafter disclosed in detail and attached to the above mentioned rope 21.

The downwardly extended portion 27' is flexible and has attached on its lower edge weights 29, as a means of securely holding the enclosing member 27 in position over the motor vehicle 28.

In Fig. 3 of the accompanying drawing I have shown a cover proper comprising a rec-

tangular frame 28, covered with any suitable material 30', preferably similar to the above mentioned sheet 16. Ropes 31 are secured to the edges of the frame 28' and are secured at 5 their extended extremities to the ropes 31', secured to a joiner 21^a hereinafter described in detail, and said joiner is attached on the above mentioned rope 21. Side extension members 32 and 33, of similar material to the 10 covering 30' of the frame 28', are secured to the edges of the frame 28' and are extended therefrom, as a means of affording ample protection to the motor vehicle 34. Ropes 35 are secured to the lower edges of the extension members 32 and 33 and are adapted to 15 securely hold the extension members 32 and 33 in position when the cover proper is in a lowered position or in use position by reason of attachment to the ground, and as a means 20 of holding the extension members 32 and 33 in a folded position under the covering 30' of the frame 28', when my improved cover is in a raised position.

Fig. 4 discloses joiner 21^a as consisting of 25 a plate 50 provided with an ear 51 on its top to which member 21 connects, and with an ear 52 on its bottom to which flexible member 21' connects. Rods 53 are pivotally connected to the plate and have arcuate side extensions 54 30 slidably engaged in standards 55 projecting from the plate 50. The standards are formed with elongated slots 56 thru which bolts 57 from the extensions 54 project so that the rods 53 may be locked at various inclinations. 35 Threaded rods 58 engage longitudinally in the rods 53 and are formed with integral hexagon portions for turning purposes. Ring members 59 are rotatively connected to the free ends of the rods 58. The various flexible 40 members which support the vehicle cover are attached to the ring 59. In operation, the rods are adjusted to inclinations as determined by the inclinations of the flexible members attached to the rings 59. One of the 45 threaded rods 58 is extended from its rod 53 and the other turns into its rod 53 so that the vehicle cover is tilted. In this tilted position the vehicle cover is lowered upon a vehicle and workers may insert their heads under the 50 higher part of the vehicle cover to make certain that it does not bear against the vehicle and cause damage.

Having thus described my invention, what I claim as new and desire to protect by Letters Patent of the United States is as follows:

1. In a device of the class described, a vehicle cover, a main rope arranged for hoisting the cover, other ropes attached on the cover, a plate member attached on the main rope, 20 rods pivotally connected on the plate member, means for adjusting the inclination of the rods, threaded rods longitudinally engaged on the rods, and rings pivotally connected on the free ends of the threaded rods, and connected with the said other ropes, so that a

hoisted vehicle cover may be tilted as desired.

2. In a device of the class described, a vehicle cover, a main rope arranged for hoisting the cover, other ropes attached on the cover, a plate member attached on the main rope, 70 rods pivotally connected on the plate member, means for adjusting the inclination of the rods, threaded rods longitudinally engaged on the rods, and rings connected on the free ends of the threaded rods, and connected with the said other ropes, so that a hoisted vehicle cover may be tilted as desired.

In testimony whereof I have affixed my signature.

VINCENZO PELLEGRINO.
